ATTORNEY

UNITED STATES PATENT OFFICE

WILLIAM P. TARRANT, OF SARATOGA SPRINGS, NEW YORK, ASSIGNOR TO TARRANT MANUFACTURING COMPANY, OF SARATOGA SPRINGS, NEW YORK, A CORPORATION OF NEW YORK

POURING POT NOZZLE

Application filed January 29, 1930. Serial No. 424,248.

This invention relates to improvements in nozzles for the distribution of viscous materials such as asphalt, tar or other heavy bituminous material which has to be heated in order to flow freely or for distributing asphalt emulsions, oil or any other desired substance. It is obvious that if such material is poured in a wide thin sheet, it is difficult to provide a nozzle which will not clog up, especially as the material loses its heat. The nozzle may be used on a hose, discharge pipe, pouring pot or in any other suitable manner. I have shown a pouring pot which is especially designed for this use in Patent No. 1,021,15 015 which was issued to me March 26, 1912.

The salient object of this present invention is to provide a nozzle for spreading or distributing material of the character mentioned, so designed that it will not clog up and can be easily cleaned.

I will describe the invention in the following specification and point out the novel features thereof in appended claims.

Referring to the drawings, 25 Fig. 1 is a side elevation of a nozzle which is made according to and embodies my invention;

Fig. 2 is a sectional end elevation of the device, the section being taken on the line 30 2-2 of Fig. 1; and

Fig. 3 is a plan view of the device shown in the preceding figures, the view being taken in the direction of the arrow 3 in Fig. 1.

Like characters of reference designate corresponding parts in the various figures of the drawings.

In the particular embodiment of the invention illustrated the nozzle is shown in combination with a pouring pot having a spout 10 of suitable construction. The outer end of the spout is tapered and of circular cross-section. The nozzle comprises a sleeve 11 which fits over the end of the spout 10 and is secured thereto by a novel spring clip 45 which will be described hereinafter. The end of this sleeve projects beyond the end of the spout and is constructed to form a discharge orifice 12 which is slightly flattened at the top as at 13.

Over the top of this discharge orifice is

affixed a baffle plate, the top of which 20 forms a flat surface in a plane which is a continuation of the longitudinal central part or top of the sleeve 11. Then it is bent downwardly on the line 21 and forms a flat apron 22 which extends downwardly across and considerably below the orifice 12 but spaced therefrom as shown clearly in Fig. 1. It will be noted that the flat portion 13 not only provides a bearing surface insuring rigidity in the joint 55 between the plate 20 and the portion 11, but forms also a slight depression so that the portion 20 will be flush with the highest point of the nozzle 11.

I will now describe the device for securing 60 the sleeve 11 to the spout 10.

30 is a guide-ring affixed to the spout 10. A wire 31 passes through this guide-ring slidingly, and its forward end is bent downwardly to form a hook 32 which engages an 65 eye 33 on the sleeve 11. The wire 31 is bifurcated to form two semi-loops 34, between which and the guide-ring is a compression spring 35 which tends to hold the hook 32 in the eye 33. From the semi-loops two 70 wires 36 extend forwardly beyond the eye 33 where they are twisted together as at 37 and then upwardly to form a finger-hold 75 38. It is a simple matter to pull the hook forwardly out of the eye 33 and to move it to the side of the eye to disconnect the catch, thereby enabling the removal of the sleeve 80 from the spout. The tapering of the member 11 insures a good tight fit with the spout 85 10 when drawn downwardly over the spout by the spring 25.

When material in a fluid condition is poured through the spout 10 and sleeve 11, it flows out through the orifice 12 and against the baffle 20, 22. The latter diverts the flow and flattens the stream into a thin flat sheet. Thus the material may be laid on a pavement, for example, in a desired manner, without passing through a narrow slit or orifice which is apt to get clogged.

Another advantage of the construction shown, is that the parts are made of metal, welded together so that as soon as use is discontinued, the sleeve may be detached from the spout and thrown on a fire or otherwise 100

heated, so that none of the poured material will adhere to it.

Although the nozzle is illustrated in connection with a pouring spout, it will be understood that it is not limited to such use but may be secured to any distributing pipe or hose.

Although one specific embodiment of the invention has been particularly shown and 10 described it will be understood that the invention is capable of modification and that changes in the construction and in the arrangement of the various cooperating parts may be made without departing from the 15 spirit or scope of the invention as expressed in the following claims.

Having thus described my invention what I claim is:

1. A nozzle comprising a tapered tubular 20 sleeve having an orifice, a baffle plate secured to said sleeve, said sleeve being flattened at a point adjacent said orifice to provide a depressed bearing surface for said plate, the depression being sufficient to locate said plate 25 flush with the extension of the nozzle therebeyond, said nozzle having an eye adjacent the end of the nozzle opposite to the baffle plate, effective to receive a retaining means for the nozzle.
- 30 2. In combination with a tapered discharge spout, a removable nozzle comprising a sleeve constructed to slip over and fit said spout, said sleeve being constructed to form a discharge orifice, a baffle plate secured to said sleeve extending downwardly in front of said orifice but spaced therefrom, and a spring catch arranged to lock the spout and sleeve together in close engagement, said catch comprising a hook slidably mounted on one of 35 said parts and an eye affixed to the other of said parts.
- 40 3. In combination with a tapered discharge spout, a removable nozzle comprising a sleeve constructed to slip over and fit said spout, 45 said sleeve being constructed to form a substantially circular discharge orifice, a baffle plate secured to said sleeve extending downwardly in front of said orifice in a plane spaced from said orifice, and a spring catch 50 arranged to lock the spout and sleeve together in close engagement, said catch comprising a wire slidably mounted on one of said parts, bent to form a hook, semi-loops and a finger hold, a spring between said loops 55 and said mounting and an eye on the other of said parts.

WILLIAM P. TARRANT.
